UNITED STATES PATENT OFFICE

WILLIAM WALLACE HANSCOM AND ALBERT LEOPOLD LANGERMAN, OF SAN FRANCISCO, CALIFORNIA.

ELECTRICAL IMMERSION-HEATER.

1,004,165.

Specification of Letters Patent. Patented Sept. 26, 1911.

Application filed March 20, 1909. Serial No. 484,750.

To all whom it may concern:

Be it known that we, WILLIAM WALLACE HANSCOM and ALBERT L. LANGERMAN, citizens of the United States, and residents of the city and county of San Francisco, State of California, have invented certain new and useful Improvements in Electrical Immersion-Heaters, of which the following is a specification.

19 The object of our improvement is to provide an immersion heater, having arrangements of parts and combinations adapted to obviate certain defects common to immersion heaters in present use, among which 15 are the comparatively long time they take to heat a given volume of liquid to a given temperature, their subjection to overheating when withdrawn from the liquid they are used to heat, and the difficulty they present 20 to thorough cleaning.

We have discovered that much of the time required to bring a given volume of liquid to a given temperature by the agency of electrical immersion heaters in common 25 use is expended in heating the parts of the heater itself, especially where such parts comprise a large proportion of electrically non-conducting material. And in the present constructions, the arrangement is such 30 that the air, being a very poor conductor, retards the rapid heating of the apparatus. By our peculiar method of combining the various parts of our device and of winding the wire, we provide a construction that 35 minimizes the amount of insulating and supporting material employed, and materially reduces the retardation due to the 40 non-conductivity of air.

The utility of providing some means of 45 preventing electrical heaters from overheating arises not only from the danger of destruction to the apparatus itself, but to the danger of setting fire to inflammable materials in juxtaposition thereto. The ordinary 50 fusing devices are useless for this purpose, because they are operated by an increase in the strength of the current flowing through them. Our protecting device operates in a different manner and does not require an increase in the current strength to cause an exercise of its function.

The necessity for keeping clean a heater that is intended to be immersed in a liquid required for human consumption, is obvious. 55 Water contains impurities which fix them-

60 selves to the surface of an immersion heater. By our construction our heater may be thrown bodily into a vessel of water, and thoroughly cleaned, without endangering the inner parts by allowing moisture to reach them.

We accomplish our object by means illustrated in the accompanying drawing of which—

65 Figure 1 is a vertical sectional view of our heater, showing fuse plug in position; Fig. 2 a plan view of our heater with parts of casing broken away to show interior mechanism; Fig. 3 the copper strip conductor, which forms an element in our scheme for winding the coil. Fig. 4 is a 70 detail view of certain connecting means.

The drawings are made to an enlarged scale in order to show the parts more clearly.

75 Similar numerals of reference mark similar parts throughout the several views.

Describing first the outer casing of our device, we provide a tube of metal 1 having a top 2, soldered thereon with solder having a very high fusing point. Attached to said top is a tube 3, which is in contact with and similarly soldered to said outer casing by high fusing solder at 4. Said top is provided with an externally threaded covering 5, for our fuse plug 6, and has a screw cap 7. Said top is also provided with an internally threaded coupling device 8, which engages with external thread on the metal tube 9, the other end of tube 9, being provided with a hermetically sealed connecting device 10, 80 which seals the inner part of said tube 85 against the entrance of moisture.

90 By the described construction of the outer covering of our heater, the inner parts thereof containing the electrical conductors and insulating materials are protected from moisture, and the whole device from connector 10 to the bottom of the outer casing 95 may be thrown into a vessel of water and thoroughly cleaned.

100 Notwithstanding the water tight character of our outer envelop, the water in which our heater may be immersed is free to flow along inner tube 3, the top and bottom thereof being open.

105 Turning now to the inner parts of our device. We provide a coil bearing tube 11, of thin brass which slips over the tube 3, inside tube 1; and the outside thereof we cover with a thin layer of mica insulation 110

12. Two contact and supporting brackets 13, and 14, are provided, bracket 14 being shaped to fit about the mica surface 12, of tube 11, substantially in the position shown. But outside of mica strip 12, and underneath bracket 13, is a conducting strip 15, said strip being laid against mica covering 12 from the top to near the bottom of the tube 11, and arranged in electrical contact 10 with bracket 13. A layer of mica 16, is placed over the conducting strip 15, and carried over the exposed surface of bracket 13. The exposed surface of bracket 14, is similarly protected from electrical contact by 15 means of a mica covering 17. Tube 11 is now placed on a former and tightly wound from top to bottom with the desired number of convolutions of bare high resistance wire 18, in such manner that a very small air 20 space is left between the convolutions. Part of these windings pass over brackets 13 and 14 as indicated in Fig. 1, and are held there firmly in position. Brackets 13 and 14 serve to support the connecting devices and fuses, 25 and, arranged as shown, obviate the necessity for using a large mass of heat absorbing substance. The bottom end of coil 18, is soldered to conducting strip 15, by solder having a very high fusing point, and the 30 top of said coil is similarly soldered to bracket 14. The surface of said coil and the interstices between the convolutions are then treated with a cold insulating cement 18' composed of silica with a solution of 35 silicate of soda.

Brackets 13 and 14 are made as small as the requirements of space and rigidity will allow, and taken in combination with the tube 12, conducting strip 15, and the thin 40 mica insulating covering described, form an element having a minimum of substance to be heated. Wherefore the temperature thereof is more quickly raised to the desired degree than is the case where more bulky 45 parts are combined after the usual manner.

Bracket 13 is provided with a connecting screw 19, to which is attached one of the insulated wires 20, from connector 10. Bracket 14 is provided with a conducting 50 plate 28 insulated therefrom whereon is attached a connecting screw 21, to which is attached a second insulated wire 23, from connector 10. Coil 18 is connected through said bracket 13 and through bracket 14, and 55 conducting plate 28, with connector 10. But bracket 14, also carries our fusing apparatus in circuit with said coil, in the manner which we will now proceed to describe.

Our fuse plug consists of a brass shell 22, 60 provided with a copper cap 23. A screw 24 is fitted to the center of said shell by means of a plug of insulating cement 25, having substantially the shape indicated, with a convex surface below and a concave surface 65 above, and an aperture through its center

stopped by said screw. A fuse wire 26, is attached to said screw and to said copper cap.

Bracket 14 is provided with an insulating strip of mica 27, which supports a conducting plate 28 and is attached thereto; and plate 28 and bracket 14 are bound together by screws 29, 30, said screws passing through screw holes made so wide in plate 28 as not to touch said screws, said screws being also 75 insulated from plate 28 by insulating washers 31 and 32.

Our fuse plug is arranged with the rim of shell 22 in electrical contact with plate 28, screw 24, being electrically insulated 80 from plate 28, and electrically attached to bracket 14. Wherefore the circuit from bracket 14, to connector 10, is through screw 24, fuse wire 26, cap 23, shell 22, conducting plate 28, connecting screw 21, and 85 wire 33.

As aforesaid, our fuse plug does not operate by an increase in the strength of the current. As the specific resistance of conducting wires increases with their temperature, 90 a raised temperature in coil 18 would tend to send a smaller instead of a greater current through the circuit. So we cause our fuse to operate directly from the heat imparted thereto by the raised temperature of 95 the whole device. Coil 18 heats all of the element and with it bracket 14 and screw 24, shell 22, and fuse wire 26. Said fuse wire being made to melt at a temperature a little above that of the whole apparatus 100 in liquid, a rise in temperature to the required degree will melt said fuse and open the circuit.

We claim:

1. In an electrical immersion heater, heating conductors and dielectrics inclosed therein, a fusing device, a protective covering for said conductors and dielectrics comprising an outer tube, having a bended portion in the lower part thereof, an inner tube having a cap adapted to fit outside said outer tube and being soldered thereto by high fusing solder, and having its lower portion fitted to engage said bended portion of said outer tube and being soldered thereto 110 by high fusing solder, a screw capped aperture in said cap adapted to protect and give ready access to said fusing device, an interiorly threaded portion on said cap, a tube threaded exteriorly at one end to engage 115 said interiorly threaded portion, and a water-tight electrical connecting device at the other end of said tube.

2. An electrical immersion heater comprising an hermetically sealed protective 125 covering having an inner tube, a coil-supporting tube surrounding said inner tube, a heating coil wound on said coil-supporting tube and insulated therefrom, supporting brackets held in position on the tube by the 130

windings of said coil, connecting screws on said supporting brackets, a water-tight electrical connector, and electrical connection between said water-tight connector, connecting screws, brackets and said heating coil.

3. An electrical immersion heater comprising an hermetically sealed protective covering having an inner tube, a coil-supporting tube surrounding said inner tube, a heating coil wound on said coil-supporting tube and insulated therefrom, supporting brackets held in position on the tube by the windings of said coil, a fuse plug supported on one of said brackets, having a fuse wire in circuit with said coil, a water-tight connector, and electrical connections between said water-tight connector and said heating coil through said fuse plug.

4. An electrical immersion heater comprising an hermetically sealed protective covering having an inner tube, a coil-supporting tube surrounding said inner tube, a heating coil wound on said coil-supporting tube and insulated therefrom, a bracket held in position on the tube by the windings of said coil, a conducting strip having an upper end in electrical contact with said bracket and a lower end of said heating coil, a second bracket held in position on the tube by the windings of said coil and electrically connected with the upper end of said heating coil, and insulated from said first bracket, a water-tight connector, and electrical connections between said water-tight connector and said brackets.

5. An electrical immersion heater comprising an hermetically sealed covering device having an inner tube, a coil-supporting tube surrounding said inner tube, a heating coil wound on said coil supporting tube and insulated therefrom, a protective fusing device including a fuse wire in circuit with said coil and arranged to be melted by excess of temperature in the adjacent parts, a water-tight electrical connector, and electrical connections between said heating coil and said connector through said fusing device.

6. In an electrical immersion heater, having a heating coil, means for protection from overheating comprising a bracket made of material as light as mechanically expedient, and having a threaded hole, a conducting plate resting thereon, but insulated therefrom, a fusing device comprising a shell, a cap on said shell, a filling of insulating cement, a screw embedded in said filling and extending beyond the lowest edge of said shell to engage said threaded hole in said bracket, an electrical connection from said bracket to the one end of said heating coil, an electrical connection from said conducting plate to an external connecting device, whereby, when said screw is threaded in said hole, said shell is seated in electrical contact with said conducting plate.

7. In an immersion heater, a heating coil, a protective covering therefor, means for electrically connecting the ends of said heating coil comprising a metal bracket held in position on the tube by the windings of said coil and electrically connected with the lower end of said coil, a second metal bracket held in position on the tube by the windings of said coil and electrically connected with the upper end thereof.

8. In an immersion heater, a tube, a heating coil wound on said tube, means for establishing electrical contact with the lower end of said coil comprising a conducting strip insulated therefrom and from said tube and held in position on the tube by the windings of said coil, an electrical connection at the top of said strip and electrical contact between the lower end of said strip and the lower end of said coil.

In testimony whereof we have set our hands this 14th day of January A. D. 1909, in the presence of the two subscribed witnesses.

WILLIAM WALLACE HANSCOM.
